United States Patent Office.

J. V. HUTSCHLER, OF KEYPORT, NEW JERSEY.

Letters Patent No. 86,756, dated February 9, 1869.

IMPROVED HAMES-FASTENER.

The Schedule referred to in these Letters Patent and making part of the same.

To all whom it may concern:

Be it known that I, J. V. HUTSCHLER, of Keyport, in the county of Monmouth, and State of New Jersey, have invented a new and improved Hames-Fastening; and I do hereby declare that the following is a full, clear, and exact description thereof, which will enable others skilled in the art to make and use the same, reference being had to the accompanying drawings, forming part of this specification.

This invention relates to improvements in devices for fastening hames of harness, the object of which is to provide a metallic fastening of cheaper and more durable construction, and more convenient to operate, than the leather straps and buckles now commonly employed.

Figure 1 represents an elevation of a pair of hames, showing my improved fastening devices in section.

Figure 2 represents an enlarged plan of the fastening.

Similar letters of reference indicate corresponding parts.

A and B represent two metallic plates, having spring-hooks, for hooking into the loops at the ends of the hames.

The plate A is provided with a flat-headed button, C, arranged to turn on its axis; and the plate B is provided with any preferred number of transverse slots, D, and a bent finger-plate, E, at one end.

The slots D will admit the head of the button C to pass through, when presented with its longest diameter in the direction of the length of the slots.

The finger-hook E facilitates the drawing together of the hames for fastening, and the disengagement of the plates, by pulling the plate B over the button.

The operation will be readily understood by inspection of the drawings.

I claim as new, and desire to secure by Letters Patent—

The plates A and B, arranged to hook into the loops of the hames, and to be connected together by the button C, secured to the plate A, and engaging the plate B through the slots, all substantially as specified.

The above specification of my invention signed by me, this 28th day of December, 1868.

J. V. HUTSCHLER.
